CLOSURE MEANS FOR FIBER CONTAINERS

John Coyle, Baltimore, Md., assignor to Continental Can Company, Inc., New York, N. Y., a corporation of New York

Application December 31, 1943, Serial No. 516,442

2 Claims. (Cl. 229—43)

The invention relates to new and useful improvements in a fiber container and more particularly to a means for closing and sealing the same.

An object of the invention is to provide a fiber container having a filling opening which is adapted to be closed and sealed by a fiber plug.

A further object of the invention is to provide a fiber container of the above type wherein the filling opening is defined by an eyelet which is rigidly attached to the end closure member.

A further object of the invention is to provide a closure means of the above type wherein the fiber plug is cup-shaped and provided with a flange for limiting the extent to which the plug can be inserted in the eyelet for closing the container.

A still further object is to provide a closure plug of the above type wherein the closed end of the plug extends into the container beyond the end of the eyelet and wherein means is provided for expanding the closed end and holding it in its expanded condition for sealing the container.

These and other objects will in part be obvious, and will in part be hereinafter more fully disclosed.

In the drawing, which shows by way of illustration one embodiment of the invention,

Figure 1 is a view partly in side elevation and partly in vertical section showing a container to which the improved closure means is applied.

Figure 2 is a plan view of the same.

Figure 3 is a view on an enlarged scale through a portion of the closure disk and the eyelet mounted therein and providing a filling opening for the container.

Figure 4 is a vertical sectional view through the fiber plug for closing and sealing the opening in the eyelet.

Figure 5 shows the plug inserted in the eyelet and the inner end of the plug expanded for locking the plug in place and sealing the container.

In the drawing there is illustrated a fiber container consisting of a body portion 1 which may be made by spirally winding, convolutedly winding or in any other suitable way. The body wall is provided with an inwardly projecting bead 2 forming a shoulder 3 on which a closure disk 4 is mounted. After the disk is placed, then the upper end of the body wall is turned inwardly over the disk as indicated at 5. As a means for firmly securing the disk to the body portion of the container, a metal ring 6 rolled into a bead 7 at the lower side thereof and into a bead 8 at the upper side thereof is placed on the container. The bead

7 is nested in the bead formed in the body wall and the bead 8 is placed at the inturned edge of the body wall, and preferably bears against the disk. This will firmly clamp the disk against the shoulder and ensure a tight sealing of the disk to the body wall.

The closure disk 4 is provided with an opening 9 therethrough. Inserted in the opening is an eyelet 10 preferably of metal, although it may be made of other rigid material. The eyelet has a flange 11 snugly contacting the outer face of the disk, and a flange 12 preferably formed by riveting to snugly engage the inner face of the disk. The disk at the immediate edge portion of the opening is clamped between these flanges 11 and 12, and this makes a very tight sealed connection between the eyelet and the disk. If desired, a sealing material could be placed between the edge of the opening and the eyelet for ensuring a very tight seal.

This opening through the eyelet may be utilized for the filling of the container. For most products the opening may be made comparatively small. After the container has been filled with the product, then the opening through the eyelet is closed by a fiber plug 13. This fiber plug is cup-shaped and is provided with a flange 14, which limits the extent to which the plug can be inserted in the eyelet. The lower or closed end of the plug projects inwardly a short distance beyond the flange 12. Located in this cup-shaped plug is a concave convex metal plate 15. When it is desired to close and seal the container, the plug is preferably coated with a suitable adhesive and then inserted in the eyelet. After the plug has been firmly seated with the flange 15 against the flange 11 of the eyelet, then a tool may be inserted in the plug and the metal plate 15 pressed upon and forced to a flat position, as shown in Fig. 5. This plate is a comparatively thin plate and can be deformed into the position shown in Fig. 5 with comparatively little pressure. This straightening out of the plate 15 will expand the inner end of the plug.

The plate is dimensioned relative to the opening through the eyelet so that when the plug is expanded the peripheral portion 16 of the plug will be of slightly larger diameter than the opening through the eyelet, and this accomplishes two functions. In the first place, it will hold the plug firmly seated in the eyelet, and in the second place, it will cause the plug to be drawn into tight sealing contact with the eyelet and thus ensure an hermetic sealing of the container.

The container described above is very rigid and

is very tightly sealed, and therefore is especially adapted for paints and similar liquid products. The end disk 4 is attached to the container by the manufacturer of the container and the final closing of the container which occurs after the product is placed in the container is of such a simple structure that it can be readily applied and tightly sealed by unskilled operators.

While a sealing material has been described as used in connection with the eyelet, and an adhesive used in connection with the plug, it will be understood that for certain uses of the container the sealing material and adhesive may be omitted. The eyelet is mechanically secured to the container end and the closure plug is mechanically secured to the eyelet for closing the container. While the plug is described as made of fiber material, it will be understood that any kind of material may be used such as metal, rubber, or the like, but it is essential that the material used shall be capable of being expanded for the securing of the plug to the eyelet without rupturing the material.

It is obvious that many changes in the details of construction may be made without departing from the spirit of the invention as set forth in the appended claims.

I claim:

1. A fiber container having an end closure disk provided with an opening therethrough, an eyelet secured to said disk in said opening, a cup-shaped

plug adapted to be placed in said eyelet for closing and sealing the container, said plug having a flange at its outer end for limiting the extent to which the plug is inserted in the eyelet, said plug being dimensioned so as to project into the container beyond the eyelet, and means disposed within said plug for expanding the inner end portion of the plug projecting beyond the eyelet to a diameter larger than the diameter of the eyelet for firmly attaching the plug to the eyelet and sealing the container.

2. A fiber container having an end closure disk provided with an opening therethrough, an eyelet secured to said disk in said opening with the flanges of the eyelet overlying the inner and outer faces of the disk, a sealing material disposed between the eyelet and the disk, a cup-shaped plug adapted to be placed in the eyelet for closing the container, said plug having a flange at its outer end, for limiting the extent to which the plug is inserted in the eyelet, said plug being dimensioned so as to project into the container beyond the eyelet, an adhesive sealing material disposed between the plug and eyelet for sealing the same and means disposed within the plug for expanding the inner end portion of the plug projecting beyond the eyelet to a diameter larger than the inner diameter of the eyelet for firmly drawing the plug into contact with the eyelet and sealing the container.

JOHN COYLE.
